UNITED STATES PATENT OFFICE.

THOMAS J. FITZGERALD, OF CLEVELAND, OHIO.

MECHANICAL ENGINE-STARTER.

1,177,504.

Specification of Letters Patent. Patented Mar. 28, 1916.

Application filed July 10, 1915. Serial No. 39,062.

To all whom it may concern:

Be it known that I, THOMAS J. FITZGERALD, a citizen of the United States, residing at Cleveland, in the county of Cuyahoga and State of Ohio, have invented new and useful Improvements in Mechanical Engine-Starters, of which the following is a specification.

This invention relates to mechanical engine starters being especially designed for use in connection with the internal combustion engines of automobiles and similar vehicles, the object of the present invention being to provide simple and novel means operable by one foot of the driver, whereby rotary motion may be transmitted to the engine shaft for the purpose of turning over the engine until it takes up its own cycle of operation.

With the above general object in view, the invention consists in the novel construction, combination and arrangement of parts, as herein described, illustrated and claimed.

In the accompanying drawings:—Figure 1 is a side elevation partly in section illustrating the starting mechanism of this invention as applied to an automobile. Fig. 2 is a cross section on the line 2—2 of Fig. 1 taken just in front of the sprocket wheel 18 of the starting cylinder. Fig. 3 is a cross section on the line 3—3 of Fig. 1. Fig. 4 is a cross section on the line 4—4 of Fig. 1. Fig. 5 is a fragmentary longitudinal section taken diametrically of the oscillatory starting cylinder.

In the drawings, the internal combustion engine is conventionally shown at A, and the shaft thereof at 1.

The starting mechanism of this invention comprises essentially a support designated generally at B and shown as comprising a base or longitudinal member 2 and other bearing members 3 substantially perpendicular to the member 2, the members 3 being formed with openings 4 for the reception of an oscillatory hollow cylinder 5. The bearing members 3 are provided with ball races 6 containing anti-friction balls 7 which form bearings in spaced relation to each other for the cylinder 5 as clearly indicated in the drawings. The bearing members 3 are shown as fastened to the base member 2 by means of bolts or screws 7 although it will, of course, be apparent that the members 2 and 3 may be integrally formed if so desired. The cylinder 5 is

spirally grooved in its inside wall or, in other words, is formed with one or more internal spiral grooves 8 with which co-operates one or more rollers 9 journaled on pins 60 10 extending radially outward at diametrically opposite points from the plunger head 11 of a reciprocating plunger 12 the rear end of which passes through the dash or floor of the machine and is provided with a 65 pedal or head 13 against which the operator presses his foot in order to thrust the plunger 12 longitudinally within the cylinder 5, causing the rollers 9 to traverse the spiral grooves 8 and thereby turn the cylinder 70 in one direction or the other in accordance with the direction in which the plunger head 11 is moving. In order to relieve friction on the plunger 12 as far as possible, the plunger 12 passes through a slotted arm 14 75 perpendicular to the base 2, said arm 14 being provided with recesses in which are arranged anti-friction rollers 15 which bear against the opposite side faces of the plunger 12 which is shown as substantially rectangular in cross section. At its forward end the cylinder 5 is provided with a diametrically reduced extension 16 and provided with a ratchet face 17.

18 designates a gear wheel, shown in the 85 form of a sprocket gear, from which a chain 19 extends around another sprocket wheel 20 on the engine shaft. The wheel 18 is provided with a ratchet face 21 adapted to engage and disengage the ratchet face 90 17 of the cylinder, the two ratchet faces being normally maintained out of co-operative relation to each other by means of a coiled expansion spring 22 interposed between the shoulder 23 of the cylinder and the sprocket 95 wheel 18. The sprocket wheel 18 is pressed toward the cylinder for the purpose of throwing the ratchet faces into engagement with each other by means of a shifting fork comprising a rock shaft 24, fork arms 25 100 100 which act to press the sprocket wheel 18 toward the cylinder, and an operating arm or lever 26 from which a suitable connection 27 extends rearwardly through the dash where it is provided with a handle 28.

105 From the foregoing description, taken in connection with the accompanying drawings, the operation of the starting mechanism will now be understood. The operator engages the head at the rear end of the plunger 12 by means of his foot and as he thrusts 110 forwardly on the plunger, at the same time

he pulls rearwardly on the connection which causes the shifting fork to press the wheel 18 rearwardly, throwing the ratchet faces 17 and 21 into engagement with each other. 5 The reciprocatory movement of the plunger-head 12 causes an oscillatory movement of the cylinder 5 and as the cylinder 5 turns in one direction, it correspondingly turns the sprocket wheel 18 and through the connections described, imparts a corresponding movement to the shaft of the engine. This 10 operation is repeated until the engine takes up its own cycle of operation.

The mechanism hereinabove described is 15 of a simple character, cheap to construct and maintain and may be used in connection with almost any make of automobile at present in use.

What I claim is:—

20 In an engine starter, the combination with the engine shaft, of a hollow oscillatory cylinder internally and spirally grooved, a support in which said cylinder is journaled, a

reduced extension at one end of said cylinder, a gear wheel slideable and normally loose on said extension and having a ratchet face, a ratchet face on the cylinder to co-operate with the first named ratchet face, means for holding said ratchet faces normally out of engagement, manually controlled means for shifting said gear wheel to engage the ratchet faces, driving means between said gear wheel and the engine shaft, a foot-operated non-rotating plunger in line with the axis of the cylinder, and a 25 plunger head arranged to be reciprocated in said cylinder and provided with means to engage the spirally grooved inside wall of the cylinder. 30 35

In testimony whereof I affix my signature 40 in presence of two witnesses.

THOS. J. FITZGERALD.
